UNITED STATES PATENT OFFICE.

JOHN NUTRY, OF RIDGEWOOD, NEW JERSEY.

NOVELTY CONTAINER.

Application filed April 18, 1922. Serial No. 555,468.

To all whom it may concern:

Be it known that I, JOHN NUTRY, a citizen of the United States, and resident of Ridgewood, in the county of Bergen and State of New Jersey, have invented certain new and useful Improvements in Novelty Containers, of which the following is a specification.

This invention relates to a novelty container and an object of the invention is to provide a container adapted for use as a bank and having the appearance of a book.

A further object is to so form the book-shaped container that altho when closed it will bear strong resemblance to a book, yet opening of one of its covers will reveal certain coin-receiving apertures while opening of the other cover will expose the deposited coins, the first cover being readily 20 opened but the second cover requiring the use of a special key.

A further and more detailed object is to make up the body portion of the book as a rectangular container open at one side, said 25 open side being closed by one of the book covers and held by a suitable key-controlled lock, the opposite side of the body being formed with a plurality of appropriately designated money, or coin-receiving apertures, and said side and apertures being normally obscured by the other cover of the book which is releasably held by a suitable snap fastener device.

A further object is to provide partition means within the body portion of the container forming separate compartments for coins of different denominations, and to adapt said partition forming means so that parts thereof will form guards to prevent 40 removal of any coin outwardly thru said slots.

A further object is to so construct the device that when the key-controlled cover thereof is open all of the coins may be made 45 to appear in readily accessible piles upon said cover.

A further object is to provide novel means whereby the coin within the bank may be counted at any time.

Other objects and aims of the invention, more or less specific than those referred to above, will be in part obvious and in part 50 pointed out in the course of the following description of the elements, combinations, arrangements of parts and applications of principles constituting the invention; and

the scope of protection contemplated will be indicated in the appended claims.

In the accompanying drawings which are to be taken as a part of this specification, and in which I have shown merely a preferred form of embodiment of the invention:

Figure 1 is a plan view of a container 65 constructed in accordance with this invention, the readily releasable cover thereof being thrown open and exposing the money-receiving slots of the body.

Figure 2 is a similar view showing the key-controlled cover thrown open and exposing the partitioned interior of the body.

Figure 3 is an edge view of the container, being partly in vertical section, substantially upon the plane of line III of Fig. 2.

Figure 4 is a similar view being partly in section substantially upon the plane of line IV of Fig. 2, and

Figure 5 is a longitudinal edge view being partly in section substantially upon the plane of line V of Fig. 2.

Referring to the drawings for describing in detail the structure which is therein illustrated, the reference character L indicates the front, or readily releasable, cover of the container, or book, while the reference character G indicates the back, or key-controlled cover of the book. These parts may be formed in any appropriate manner and are preferably covered by a suitable binding material so that they are substantially the same in exterior appearance to any ordinary book covers.

The body of the container, or book, is indicated generally by the reference character H and corresponds in exterior appearance to the leaf portion of the book. An appropriate binder portion, as 90 1, is provided at one edge of the body, and the covers L and G are hinged thereto preferably by hinges, as indicated 2, so that the covers are free to swing open to expose the opposite sides of the body H.

Upon the front cover L is provided one or more snap fastener lug elements, as 3, adapted to frictionally engage within apertures 4 of the body so that said cover may be temporarily held closed but may be readily opened wherever desired.

The cover G carries one or more lugs 5 so disposed as to firmly interengage with latch elements 6 of the body when said cover is closed, said latch elements forming parts

of a lock mechanism, as indicated 7, carried by the body and adapted to be controlled by a key, as 8.

The body H is rigidly connected with the binder portion 1 of the book and consists of a front wall 9, end edge walls 10 and 11, and a side edge wall 12. The front wall 9 is shaped to provide a marginal rib 13 against which the cover L rests when closed, said rib and cover being adapted thereby to define a suitable open space, or compartment, 14, between said front wall and the cover when the cover is closed for containing a suitable bank, or memorandum, book such as may be appropriately kept always with the bank.

The central portion of the front wall is depressed, as at 15, so as to provide a ledge 16 thru which is formed coin slots 17, 18 and 19, and an opposite ledge 20 thru which is formed coin slots 21, 22 and 23, said slots being thus disposed so that the operation of inserting the coins may be performed by resting the coins flat upon the depressed portion 15 and by sliding them laterally into the slots and beneath the relatively raised portions 24 of the front wall.

The front wall may also be provided with a slot, as 25, thru which paper money, or the like, may be inserted.

The relatively raised portions 24 of the front wall are provided with eight apertures 26 therethru one for each of the coin slots and disposed so that the coins deposited in the respective slots may be seen and inspected at any time.

The snap fastener openings 4 occur in this front wall and, as above suggested, it is intended that the cover L, when closed, shall cover and conceal all of the coin slots and other features of the front wall described.

The end and side edge walls 10, 11 and 12, are preferably formed integrally with the front wall, being bent upwardly therefrom and the outer surfaces being polished, or otherwise treated, so as to resemble the leaf edges of an ordinary book.

The rear side of the body is entirely open and the only closure therefor is the cover G of the book.

Within the body is fixed a partition forming member A consisting of a plate 27 having opposite marginal wall parts, as 28 and 29, bent up therefrom to the outer surfaces of which are connected partition forming members 30 and 31 respectively.

The plate 27 is arranged to lie flat against the inner surface of the depressed portion 15 of the front wall 9 of the body, and has an opening, as 32, formed therein registering with the slot 25 of said front wall so as not to interfere with the free introduction of paper into the interior of the body.

The walls 28 and 29 constitute transverse partitions within the body substantially un-

derlying the ledges 16 and 20 of the front wall and thereby dividing the interior of the body into a central paper-money receiving compartment, as 33, and opposite, or outer coin receiving compartments, as 34 and 35.

The partition member 30 is shaped to define within the compartment 34 a plurality of separate stalls, as 36, 37 and 38, one for each of the slots 17, 18 and 19.

The partition member 31 is shaped to define within the compartment 35 a plurality of separate stalls, as 39, 40 and 41, one for each of the slots 21, 22 and 23.

The eight apertures 26 register one with each of the several stalls and are intended to afford a view of any coins within the stalls, particularly to the extent that the number of coins contained within each stall at any particular time may be counted by the assistance of a scale, as 42, which it is intended shall be printed, or otherwise impressed on, to the outer side surfaces of the walls 28 and 29, one scale within each stall.

Any suitable means may be provided for preventing removal of coins outwardly thru the coin slots, but as a simple expedient to this end the drawing herein shows the plate 27 to be cut in a manner so as to provide a plurality of spring fingers, as 43, which project one or more into each of the stalls, the ends, as 44, of said fingers within the stalls being bent so as to stand in an inclined position across the money slots as best indicated in Fig. 5. When a coin is moved into the slot the pressure of the coin will readily move the fingers aside so as to permit the coin to pass. Once inside retrogressive movement, however, will be positively obstructed by the inclined portion of the fingers.

The lock mechanism 7 employed may be of any suitable type but preferably is constructed and made to operate in substantially the same manner as shown and described in my copending application, Serial No. 555,469. The casing for the movable parts of this mechanism may be conveniently formed by arranging an up-turned wall portion, as 45, of the plate 27 so that it will stand spaced from and substantially parallel with the inner surface of the side edge wall 12 of the body, thus leaving a cavity between said two walls.

The rib 13 of the front wall of the body may be proportioned so that its interior will constitute a part of this cavity, as seen in Fig. 4, and an edge portion, as 46, of the wall 12 of the body may be bent to overlap an adjacent edge portion of the wall 45 so as thus to hold all of said parts rigidly assembled.

It will be seen from this description that if the book be laid upon its side with the cover G lowermost, all of the coins, as indi-

cated by the reference numeral 47, within the several stalls will stand in neat piles upon the then upper surface of the cover G and that any paper money contained within

5 the compartment 33 will likewise rest upon the upper surface of the cover G in position between the piles of coins. If now the body be swung upwardly the coins and paper money will be left resting in this 10 manner upon the cover G and readily accessible, the coins of different denominations being in different piles so that they may be readily handled and counted.

As many changes could be made in this 15 construction without departing from the scope of the invention as defined in the following claims, it is intended that all matter contained in the above description, or shown in the accompanying drawings, shall be interpreted as illustrative only and not in a limiting sense.

Having thus described my invention, what I claim as new and desire to secure by Letters Patent is:—

25 1. A book-shaped bank comprising a body portion and front and back covers arranged to swing into and out of closed position against the body portion, the body portion having a front wall beneath the front cover, said front wall having a money slot therein thru which coins may be inserted into the body, the back cover constituting a closure for the otherwise open back of the body, the front cover being readily openable, and 30 means whereby the back cover may be locked against opening by unauthorized hands.

2. A book-shaped bank comprising a body portion and front and back covers arranged to swing into and out of closed position 40 against the body portion, the body portion having a front wall beneath the front cover, said front wall having a plurality of money slots therethru thru which coins may be inserted into the interior of the body, means dividing the body into a plurality of stalls one for containing the coins introduced thru each of the respective slots, the back cover constituting a closure for the otherwise open body and stalls, the front cover being readily 45 openable, and means whereby the back cover may be locked against opening by unauthorized hands.

3. A book-shaped bank comprising a body portion and front and back covers arranged 55 to swing into and out of closed position against the body portion, the body portion having a front wall beneath the front cover, said front wall having a depression therein defining an upstanding ledge, said ledge 60 having a money slot formed therethru, thru which coins may be inserted into the body, means within the body forming a stall within which the coins will pile one upon the other, the back cover constituting a closure 65 for the otherwise open back of the body

and stall, thus constituting a surface upon which the pile of coins may rest, and means to retain said back cover against accidental opening.

4. A book-shaped bank comprising a body portion and front and back covers arranged to swing into and out of closed position against the body portion, the body portion having a front wall beneath the front cover, said front wall having a slot therein thru which paper money may be inserted into the body, said front wall also having a further slot therethru thru which coins may be inserted into the body, means within the body 70 dividing the interior thereof into one compartment for receiving the paper money and another compartment for receiving the coins, the back cover constituting a closure for the otherwise open back of said body and compartments, thus constituting a surface upon which the pile of paper money may rest separate from the coins, and means to retain said back cover against accidental opening.

5. A book-shaped bank comprising a body portion and front and back covers arranged to swing into and out of closed position against the body portion, the body portion having a front wall beneath the front cover, said front wall having a central depressed portion and opposite relatively raised portions, the juncture between said mentioned portions comprising ledges having money slots therein thru which coins laid flat upon the central portion may be slid laterally 90 into the interior of the body, means within the body defining stalls one for each of said money slots and within which the coins may be received piled one upon another, and means whereby the body may be lifted away 95 to leave said piles readily accessible.

6. A book-shaped bank comprising a body portion and front and back covers arranged to swing into and out of closed position against the body portion, the body portion having a front wall beneath the front cover, said front wall having a central depressed portion and opposite relatively raised portions, the juncture between said mentioned portions comprising ledges having money slots therein thru which coins laid flat upon the central portion may be slid laterally into the interior of the body, means within the body defining stalls beneath the relatively 110 raised portions one for each of said money slots and within which the coins may be received piled one upon another, said front wall having a further slot therethru thru which paper money may be inserted into the body beneath the relatively depressed portion of the front wall in the space between said stalls, the body and front cover of the book having interengaging snap fastener means whereby said front cover is readily 115 openable for giving access to said slots, the

back cover constituting a closure for the otherwise open back of said body and stalls and constituting a surface upon which said paper money and the piles of coins may rest, 5 and means whereby said back cover may be locked against opening by unauthorized hands.

7. A book-shaped bank comprising a body portion and front and back covers arranged 10 to swing into and out of closed position against the body portion, the body portion having a front wall beneath the front cover, said front wall having a depression therein within which a bank book, or the like, may 15 be conveniently contained, said front wall also having a money slot formed therethru thru which coins may be inserted into the interior of the body, the back cover constituting a closure for the otherwise open 20 back of the body, the front cover being readily openable, and means whereby the back cover may be locked against opening by unauthorized hands.

8. A book-shaped bank comprising a body portion and front and back covers arranged 25 to swing into and out of closed position against the body portion, the body portion having a front wall beneath the front cover, said front wall having a money slot therethru 30 thru which coins may be inserted into the interior of the body, means within the body defining a stall within which the coins will be retained in pile formation, said front wall having a sight opening therethru, and a 35 scale provided upon said stall forming means visible thru said sight opening by which to count the coins within the stall.

9. A book-shaped bank comprising a body portion and front and back covers arranged 40 to swing into and out of closed position against the body portion, the body portion having a front wall beneath the front cover, said front wall having a money slot therethru thru which coins may be inserted into 45 the interior of the body, means within the body defining a stall within which the coins will be retained in pile formation, and a guard device comprised in said stall forming means adapted to prevent egress of coins 50 outwardly thru said slot.

10. A book-shaped bank comprising a body portion and front and back covers arranged to swing into and out of closed position against the body portion, the body portion having a front wall beneath the front cover, said front wall having a plurality of money slots therethru thru which coins may be inserted into the interior of the body, a 55 partition forming device contained within the body comprising parts constituting stalls, one for each of said slots, within which coins deposited thru the respective slots will be retained in pile formation, and said partition forming means having parts 60 also disposed to constitute guard devices ad-

acent the several slots adapted to prevent egress of coins outwardly thru the slots.

11. A receptacle adapted to be used as a bank, means within the receptacle dividing the interior thereof into spaced compartments, one adapted to receive coins therein and the other to receive articles such as paper money therein, the upper wall of the receptacle having a relatively raised portion overlying the coin receiving compartment and a relatively depressed portion overlying the other compartment, said upper wall also having a slot through which paper money may be inserted, the juncture between the relatively raised and the relatively depressed portion of said upper wall providing a ledge having a slot through which coins may be inserted into the coin compartment, and the relatively depressed portion providing a surface upon which coins may be laid and across which they may be slid through said last slot.

12. A receptacle adapted to be used as a bank, means within the receptacle dividing the interior thereof into spaced compartments, one adapted to receive coins therein and the other to receive articles such as paper money therein, the upper wall of the receptacle having a relatively raised portion overlying the coin receiving compartment and a relatively depressed portion overlying the other compartment, said upper wall also having a slot through which paper money may be inserted, the juncture between the relatively raised and the relatively depressed portion of said upper wall providing a ledge having a slot through which coins may be inserted into the coin compartment, the relatively depressed portion providing a surface upon which coins may be laid and across which they may be slid through said last slot, and the material of said upper wall adjacent said last slot being shaped to provide guard means disposed to prevent egress of coins outwardly 105 through said last slot.

13. A receptacle adapted to be used as a bank, means within the receptacle dividing the interior thereof into spaced compartments, one adapted to receive coins therein and the other to receive articles such as paper money therein, the upper wall of the receptacle having a relatively raised portion overlying the coin receiving compartment and a relatively depressed portion overlying the other compartment, said upper wall also having a slot through which paper money may be inserted, the juncture between the relatively raised and the relatively depressed portion of said upper wall providing a ledge having a slot through which coins may be inserted into the coin compartment, the relatively depressed portion providing a surface upon which coins may be laid and across which they may be 120 125 130

slid through said last slot, and the material of said upper wall adjacent said last slot being cut to provide spring fingers, continuing from the depressed portion thereof and 5 disposed to provide guard means adjacent said last slot to prevent egress of coins outwardly through the last slot.

In testimony whereof I affix my signature in the presence of two witnesses.

JOHN NUTRY.
